LASTING MACHINE

Bernhardt Jorgensen, Beverly, Mass., assignor to
United Shoe Machinery Corporation, Paterson,
N. J., a corporation of New Jersey

Application March 5, 1934, Serial No. 714,009

93 Claims. (Cl. 12—12)

This invention relates to lasting machines, and is herein illustrated as applied to a machine organization of the same general character as disclosed in Letters Patent No. 1,843,232, granted upon an earlier application of mine of February 2, 1932, but modified in certain respects as further disclosed in Letters Patent No. 1,979,269, granted on November 6, 1934, upon another application of mine. Such machines have been utilized heretofore in the manufacture of tennis shoes and other shoes having rubber shoe bottom parts which are vulcanized while the shoes are on their metal lasts, and have also been used to some extent in the manufacture of other kinds of footwear made on wooden lasts in which there are more pronounced differences as between rights and lefts than in the above-mentioned metal lasts, including footwear in which portions at least of the uppers are made of leather as distinguished from the fabric of which tennis shoes and the like are commonly made. Objects of the present invention, in certain aspects, are to provide improvements such as to adapt the machine for better results in operating upon such other kinds of footwear made on wooden lasts, although it is to be understood that the invention is not limited in utility to the manufacture of any particular kind of footwear. It is also to be understood that the invention, in various aspects, is not limited to machines of the type illustrated in the above-mentioned Letters Patent.

In machines of the above-mentioned type, as heretofore constructed, the position of each last and shoe with respect to lengthwise movement has been determined by a heel pin engaging the heel end of the last in its spindle hole. In view of the frequent lack of uniformity in the positions of the spindle holes in different lasts, the present invention provides novel means whereby the lengthwise position of each last and shoe is determined by contact with the heel end face of the shoe, so that the toe end faces of all lasts of the same length are positioned in invariable relation to the toe-lasting mechanism regardless of variations in the locations of the spindle holes, thus insuring substantially uniform results in the toe-lasting operations without the necessity for frequent adjustments. The machine herein shown is provided as heretofore with heel-end-clamping means which is moved lengthwise of each shoe toward its heel end after the shoe and its last have been mounted on the shoe support, and for purposes of the present invention there is further provided means for positively limiting such movement of the clamping means and also

means for imparting to the shoe support a movement to carry the heel-end face of the shoe into contact with the clamping means. More particularly, the construction shown comprises a spring for thus moving the shoe support, and mechanism for releasing the spring to render it operative in response to movement of the clamping means toward the shoe when the clamping means has arrived substantially at the limit of its movement. The heel-end-clamping means is thus utilized to determine the lengthwise position of each last and shoe without in any case imparting a forward movement to the last such as might under some conditions tend to displace the toe end of the last relatively to the upper assembled thereon.

In accordance with another feature, the invention provides novel means for determining the positions of lasts and shoes with respect to movements about longitudinal axes, so that the bottoms of right and left shoes will lie in proper relation to the lasting mechanism. As herein illustrated, a more particular object thus in view is to position each last and shoe, whether a right or a left, so that the bottom of the toe end of the shoe will extend widthwise in directions substantially parallel to the plane of the toe wipers. For this purpose, in the construction shown, the last pin is movable in such manner as to permit each last and shoe to be tipped laterally as required when the operator presents the work to the machine, and such tipping of the last is adjustably limited by a stop engaging a side face of the heel end of the last, opposite stops being provided for positioning right and left lasts respectively. As illustrated, the movement of the last pin is in a curved path about an axis located approximately at the bottom of the heel end of the shoe. In this manner each last and shoe is positioned quickly and accurately in proper relation to the toe wipers regardless of variations in the locations of the spindle holes in the different lasts.

In a further aspect, the invention provides improved means for controlling end-lasting wipers, herein shown as the heel wipers, in movements which they receive to position them in proper relation to the shoe. In machines of the illustrated type the heel wipers are supported in part by members or plungers located respectively beneath the different wipers and relatively movable heightwise of the shoe to permit tipping of the wipers laterally of each shoe to a position determined by a presser foot engaging the heel end of the insole. In the construction herein shown these wiper-supporting members are so

controlled as to oppose no resistance to the tipping of the wipers, the two members resting on an equalizing lever which is freely movable so that as either of the members is depressed by 5 the tipping of the wipers the other member is simply raised a corresponding distance. As further illustrated, the equalizing lever is also bodily 10 depressible against yielding resistance to permit such bodily depression of the wipers as likewise occurs in the operation of the machine.

Another feature of the invention is to be recognized in improved means for clamping an upper about an end of a last, herein shown as toe-clamping means having the further function of 15 wiping the upper heightwise of the last. As illustrated, this means comprises a flexible toe band having a flaring shape such as to present an edge portion only in contact with the upper, together with novel means for supporting and 20 controlling the band in such manner as to permit it readily to conform to the contour of the shoe, including swinging arms supporting the ends of the band and a plurality of slides supporting other portions and yieldingly movable relatively to one another in response to pressure of 25 the shoe on the band. To increase the effectiveness and durability of the band, especially in wiping the upper heightwise of the last, the invention further provides a band having a layer of celluloid for engaging the upper and another layer of 30 different flexible material, preferably leather, for reinforcing the layer of celluloid.

Machines of the illustrated type have been provided heretofore with flexible straps for 35 forming the upper to the last and for laying its margin inwardly over the insole in locations substantially at the ends of the toe wipers. In the construction herein shown the toe band is extended to operate on portions of the sides of the 40 shoe in place of these straps, and for laying the margin of the upper over the insole in corresponding locations there are provided rolls which are moved inwardly with the toe wipers. As illustrated, these rolls are carried by arms which 45 swing as heretofore about axes extending heightwise of the last and carry wiper plates arranged to operate at the sides only of the toe, as distinguished from other wiper plates operating around the end of the toe. The rolls are so 50 arranged that they begin to lay the upper over the insole before the above-mentioned side wiper plates begin to wipe the upper inwardly, thus affording further insurance against undue displacement lengthwise of the shoe of portions of 55 the margin of the upper near these side plates, and also further insurance that the margin of the insole over which the upper is wiped by these plates will lie close to the bottom of the last in the overwiping operation.

60 In accordance with further features of the invention improved means are provided for controlling the margin of the insole and also the margin of the upper around the toe end of the last. As herein illustrated, the toe end of the 65 insole is engaged by a clamping device portions of which are moved relatively to one another in outward directions toward the edge of the insole while in contact with the bottom face of the insole so as to insure that the margin of the 70 insole around the toe will lie close to the bottom of the last, this device being also arranged to press the upper against the incoming toe wipers and thus to serve as a retarder or spreader to maintain the margin of the upper free from 75 wrinkles while increasing the effectiveness of

the edges of the wipers on the upper in wiping the upper tightly over the insole. Combined with this insole-clamping device in the construction herein shown is also a device for clamping the margin of the upper upon the toe wipers 5 prior to depression of the last relatively to the toe band and the wipers, so that as the last is depressed a pull is applied to the upper in addition to the upwiping action of the toe band. As further herein illustrated, both clamping devices are carried by an arm with which machines of the illustrated type are provided for depressing the toe end of the last, and mounted also on this arm is mechanism which is operated by the toe-wiper-operating means to move the in- 10 sole-clamping device toward the edge of the insole as above described, and also to impart to the upper-clamping device a movement lengthwise of the shoe in time relation to the operation of the wipers.

20 The above and other features of the invention, including also a novel end band having a detachable portion, novel means for determining the position of the last and shoe laterally, and various novel details of construction and combinations of parts, will now be more particularly described by reference to the accompanying drawings and pointed out in the claims.

In the drawings,

Fig. 1 is a view in front elevation of the upper 30 portion of a machine in which the features of the invention are embodied, showing the parts in the positions which they occupy after the heel-end-clamping means and the shoe support have received their movements toward each other, 35 but prior to the starting of the power operation of the machine;

10 Fig. 20 is a section on the line XX—XX of Fig. 17;

Fig. 21 is a vertical central section through a portion of the toe-lasting mechanism and the means for controlling the upper and the insole, showing the parts in the positions which they 15 occupy immediately prior to the depression of the last; and

Fig. 22 is a view similar to Fig. 21, showing the parts in the positions which they occupy just after the beginning of the operative movement of the 20 toe wipers.

In view of the disclosure in the previously mentioned Letters Patent, only such parts of the machine as it is necessary to refer to for an understanding of the invention will be hereinafter 25 mentioned. The last with the upper and insole thereon is mounted on a last pin 2 which enters the spindle hole in the heel end of the last and is supported on a vertically movable slide 4 (Fig. 1) which at a predetermined time in the cycle of 30 the machine is forced downwardly with the last and shoe against the resistance of a spring 6 by pressure applied on the bottom of the shoe, as fully disclosed in the previously mentioned Letters Patent. The last pin 2 is mounted by means 35 hereinafter described on the upper end of a vertical rod 8 which has screw threads engaged by cooperating threads in a bevel-gear 10 (Fig. 2) rotatably mounted in a slide 12, this slide being mounted for movements in directions lengthwise 40 of the shoe along guideways 13 on the upper end of the vertically movable slide 4 for a purpose hereinafter described. The bevel-gear 10 is engaged by a bevel-gear 14 fast on a shaft 16 which is rotatable in the slide 12 and extends through a 45 slot 18 in the vertically movable slide 4 to permit the above-mentioned movements of the slide 12 lengthwise of the shoe, the shaft 16 having a hand wheel 20 thereon for turning it. It will be understood that by this means the rod 8 is adjusted vertically as required for shoes of different 50 sizes.

The heel-lasting mechanism comprises wipers 22 (Fig. 1) for wiping the margin of the heel end of the upper inwardly over the insole and a heel-end-clamping device or heel band 24 for clamping the upper around the heel end of the last. The wipers and the heel band are carried as heretofore by a slide 26 guided for movements lengthwise of the shoe on a pair of horizontal rods 28 (Figs. 1 and 2) which are mounted on the vertically 55 movable slide 4. To provide room for mounting the work on the last pin 2 the slide 26 is maintained initially in an idle position comparatively remote from the shoe support by a latch 30 (Fig. 1) in engagement with a lug 32 on the lower end of the slide 26, and upon its release by the latch 30 the slide is moved toward the shoe by a spring 34 (Fig. 2) which abuts at its outer end against a bracket 36 fast on the rods 28. The latch 30 is carried by a lever 38 which, through a rod 40, is moved downwardly by the operator as heretofore to release the slide 26 to the action of the spring 34 after the shoe has been placed on the shoe support.

75 In the construction herein shown the move-

ment which the slide 26 receives from the spring 34 is not limited by contact of the heel band 24 with the shoe on the shoe support, as heretofore, but by washers 42 (Fig. 2) mounted on the rods 28 and abutting against the vertically movable slide 4, and the shoe is carried into engagement with the heel band by a short movement of the previously mentioned shoe support slide 12 toward the slide 26 along the guideways 13 on the upper end of the slide 4. For controlling the 10 slide 12 there is provided another slide 44 (Figs. 1, 2 and 8) movable along a guideway 46 formed on a bracket 48 which is fast on the slide 4. Rotatably mounted in the slide 44 is a shaft 50 which carries a bevel-gear 52 in engagement with another bevel-gear 54 on a shaft 56 at right angles to the shaft 50 and also rotatably mounted in the slide 44. The shaft 56 is provided with screw threads engaging cooperating threads in a nut 58 mounted in the slide 12. On the shaft 50 is a 20 hand-wheel 60 for turning it. It will thus be seen that by turning the hand-wheel 60 the slide 12 may be adjusted in directions lengthwise of the shoe relatively to the slide 44 as may be required for shoes of different sizes, and that the 25 slide 12 and the slide 44 are held by the adjusting means in fixed relation to each other so as to be movable as a unit in directions lengthwise of the shoe.

Pivottally connected at one end to a pin 62 in 30 the slide 44 is a link 64 which is pivotally connected at its other end to a crank arm 66 fast on a shaft 68, this shaft being mounted to turn in the bracket 36. On the hub of the crank arm 66 are gear teeth 70 in engagement with a pinion 35 72 which is fast on a shaft 74 also mounted to turn in the bracket 36. Fast on the shaft 74 is a depending arm 76 the lower end of which is in the path of the horizontally movable slide 26. It will thus be seen that when the slide 26 is 40 moved outwardly to its initial position where it is held by the latch 30, as it is automatically near the end of the cycle of the machine through connections to a chain 78 as heretofore, it acts through the arm 76 and the gearing 72, 70 to 45 move the link 64 toward the left (Fig. 1) and thus to move the slide 44 and the shoe support slide 12 also to the left, thereby carrying the shoe lengthwise in a direction away from the heel band 24 which is being moved in the opposite 50 direction away from the shoe by the slide 26. Such movement of the link 64 results in compression of a spring 80 held between a nut 82 on the link and a plate 84 fast on the bracket 48. The slide 44 and the connected slide 12 are held 55 in the positions to which they are thus moved by the link 64 by means of a latch 86 pivoted on the bracket 48 and controlled by a spring 88, this latch engaging a plate 90 on the slide 44. Accordingly when the slide 26 is released by the latch 60 30 after the next shoe has been mounted on the shoe support, the shoe support slide 12 is held in its initial position by the latch 86 as the slide 26 is moved toward the shoe support by the spring 34. When the slide 26, however, has near- 65 ly reached the position in which it is stopped by the washers 42, a screw 92 adjustably mounted in the lower end of this slide comes into contact with a depending arm 94 of the latch 86 and causes the latch to release the slide 44. There- 70 upon the spring 80 by its pressure on the nut 82 impels the link 64 toward the right (Fig. 1), since the arm 76 is no longer against the slide 26, and thereby forces the shoe support slide 12 toward the right until it is stopped by contact 75

of the heel end face of the shoe with the heel band 24. It will thus be seen that the lengthwise position of each shoe is determined by the heel band in contact with the heel end face of the shoe, and since the heel band is moved each time to the same position determined by the washers 42, the toe end faces of all lasts of the same length are positioned in the same relation to the toe-lasting mechanism regardless of any variations that there may be in the locations of the spindle holes in the different lasts. This contributes to uniformly satisfactory results in the lasting of toes without the necessity for frequent adjustments. It will further be evident that the provision of means for holding the shoe support slide 12 retracted until the heel band has approximately arrived at its limit of movement and for then operating the slide to carry the shoe against the heel band serves to avoid any such forward movement of the last as might otherwise occur by reason of the pressure of the heel band on the shoe with possible resulting displacement of the toe end of the last relatively to the upper.

25 The heel-end-clamping device or heel band 24, similarly to the construction disclosed in the previously mentioned Letters Patent No. 1,843,232, comprises a chain of connected links 96 (Fig. 3) arranged to extend about the heel end 30 of the shoe, the opposite ends of the chain being connected to blocks 98 which are pivotally connected by pins 100 to the front ends of levers 102, these levers being fast on vertical rock-shafts 104 mounted on the horizontally movable slide 26. The chain of links 96 is supported centrally by means of a finger 106 extending from it and slidably mounted in an opening in the slide 26. A flexible strip or band of leather 108 is fastened to the blocks 98 and to the intermediate link 96 by screws 110 the heads of which are countersunk in the leather strip, as illustrated in Fig. 4. Since the heads of the screws are thus spaced from the inner surface of the strip 108, the latter may, if desired, be used as the shoe-engaging portion of the heel band in direct contact with the upper. To insure, however, against contact of the heads of the screws with the upper if the strip 108 should become worn through long continued use, and also to provide means whereby the heel band may be conveniently contracted so as to present a smaller shoe-receiving opening for use on comparatively small shoes, the construction herein shown comprises a second flexible leather strip or band 112 fastened detachably to the strip 108 by means located well below that portion of the heel band which is applied in firm clamping engagement with the upper. This means consists of snap fasteners one of which is shown in section in Fig. 4 as consisting of two interlocking parts 114 and 116 mounted respectively in the leather strips 108 and 112 and readily detachable from each other by pulling them apart. Preferably three of these fasteners will be used, one located 65 near each end of the heel band and one located at the intermediate portion of the band.

70 The levers 102 which support the heel band are controlled by a spring 118 connected as heretofore to arms of the levers which are on the opposite sides of their fulcrums from the arms that support the band and tending to swing the latter arms apart, although permitting them to be drawn toward each other by pressure of the end face of the shoe against the intermediate 75 portion of the band. Associated with the levers

102 is means of the same character as disclosed in the previously mentioned Letters Patent No. 1,979,269 for controlling the levers in such manner that the heel band has normally a contour approximately such as it assumes when in 5 clamping relation to the shoe and is also substantially centralized laterally with respect to the heel end of the shoe. This means comprises a pair of connected arms 120 arranged to serve adjustably as limit stops for the outer ends of the 10 levers 102, together with other parts which it is unnecessary to describe for an understanding of the present invention.

In general similarity to the disclosure of the previously mentioned Letters Patent, the machine 15 is provided with toe-lasting mechanism including toe wipers, hereinafter more particularly referred to, for wiping the margin of the toe end of the upper inwardly over the insole. It is necessary for the proper operation of these wipers on the 20 upper that the plane in which they operate shall be substantially parallel to the general plane of the bottom of the toe end of the last or shoe. To provide for such parallelism in directions lengthwise of the last in operating on lasts of different 25 styles the machine is provided as heretofore with means for adjusting the toe-lasting mechanism about an axis extending widthwise of the last. There is, however, no provision for adjustment of the mechanism about an axis extending lengthwise of the last, and accordingly the last must be so positioned that the bottom face of its toe-end portion will extend widthwise in substantially parallel relation to the plane of the wipers. If wooden lasts of the usual styles are thus positioned, 30 however, the spindle holes in the heel ends of right and left lasts are inclined respectively in opposite directions in the machine. In general similarity, therefore, to the disclosure of the previously mentioned Letters Patent No. 1,979,269, the last pin 2 which enters the spindle holes of the different lasts is not fixed to the rod 8, but is so mounted that it may be tipped relatively to the rod toward the front or toward the rear of 35 the machine in accordance with the inclinations of the spindle holes in the right and left lasts. For this purpose the last pin is fast on a slide 122 (Figs. 5 and 6) having flanges which extend into guideways 124 formed in a head 126 on the rod 8, these flanges and guideways being curved 40 laterally of the shoe and last about an axis located approximately at the bottom face of the heel end of a shoe on a last of average height. By movement of the slide 122 the last pin may be tipped as required without any substantial bodily 45 lateral displacement of portions of the heel end of the shoe near its bottom face, so as not to alter to any substantial extent the relation of the last and shoe to the opposite side portions of the heel band. In the construction herein shown there is no provision for fixing the slide 122 in any definite relation to the rod 8, the slide being 50 freely movable along its guideways so that after mounting each last on the last pin the operator may tip the last laterally to bring the bottom of its toe end into proper relation to the plane of the toe wipers. In order, however, to relieve the operator of the necessity of exercising any particular care in the positioning of each last, and to insure uniformity in the positioning of different 55 lasts, the machine herein shown is provided with means for limiting the tipping of each last in the manner above described by contact with a side face of the heel end of the last. This means comprises a pair of stops or abutments 128 lo- 60

75

cated at opposite sides of the last pin 2 in positions to contact with the side faces of the heel ends of lasts, these stops being adjustably movable along a dovetailed guideway 130 formed on the head 126 of the rod 8. For adjusting the stops there is provided a rod 132 having right and left threads thereon in engagement respectively with the different stops, this rod being rotatable by means of a knurled head 134 thereon and having midway between its ends a diametrically enlarged portion 136 which lies in a slot in the head 126 to prevent lengthwise movements of the rod. By turning the rod 132 the stops 128 may thus be adjusted equal distances toward or from each other.

In operating on shoes made on lasts of a particular style the operator will first mount a last on the last pin 2 and will tip the last and the last pin until the outer side face of the heel end of the last engages that stop 128 which is at that side of the last. By turning the rod 132 the operator will then adjust the two stops 128 until the last is so positioned that the bottom of its toe end extends laterally in directions substantially parallel to the plane of the toe wipers. Such an adjustment will thereafter serve for all lasts of the same style, whether they are rights or lefts, the operator tipping each last to the position determined by one or the other of the stops, in accordance with whether it is a right or a left last, in presenting the work to the machine. It will be evident that the accuracy of this positioning means is unaffected by any variations in the locations of the spindle holes in different lasts.

The heel-lasting wipers 22, in general similarity to the disclosure of the above-mentioned Letters Patent No. 1,979,269, are mounted for swinging or closing movements on a vertical stud 138 (Fig. 7) carried by the head of a plunger 140 (see also Fig. 1) which serves as a wiper carrier and is mounted for lengthwise movements and for turning movements in a holder 142 supported as herein-after described. The wipers are advanced lengthwise of the shoe by forward movement of the plunger 140 effected by the operation of a bell-crank lever 144 which carries a plate 146 arranged to engage a roll 148 on the end of the plunger. As the wipers are thus advanced lengthwise of the shoe they are closed laterally of the shoe about the stud 138 by a pair of links, one of which is shown at 150 (Fig. 1), controlled by pins 152 on a member 154, as fully disclosed in Letters Patent No. 1,979,269. In general similarity also to the prior disclosure, the wipers 22 are supported initially in a position higher than their operating position, and prior to their operation on the shoe they are depressed to a position determined by the height of the bottom face of the heel end of the shoe and are also tipped laterally of the shoe about the axis of the plunger 140 to position them at an inclination corresponding substantially to whatever lateral slope the bottom face of the heel end of the last may have after the last has been positioned in the manner hereinbefore described. For thus supporting the wipers, the previously mentioned holder 142 is mounted on a plunger 156 (Fig. 1) which is movable vertically in a recess in the slide 26 and is depressible against the resistance of a spring 158, and the heel-band-supporting levers 102 are further provided with plungers 160 (Figs. 1, 3 and 7) which contact with the lower faces of the wipers. In the construction herein shown the plungers 160 are not upheld by separate springs in the levers 102 as in the earlier construction,

but are controlled by different means hereinafter described. The holder 142 is supported on the plunger 156 by trunnions 162 which permit tipping of the wipers 22 about an axis extending laterally of the shoe, and the wipers are held at all times in contact with the tops of the plungers 160 by a spring 164 which tends to tip the holder 142 in one direction.

The wipers 22 are depressed and are positioned in proper relation to the plane of the heel end of the insole on the last by the operation of a carrier 166 (Fig. 1) fast on a vertical rod 168 which is mounted for downward and upward movements and for turning movements in the frame of the machine. This carrier is swung from an idle position, in which it is shown in Fig. 1, to an operating position, and is then moved downwardly to depress and position the heel wipers and thereafter to depress the last and shoe together with these wipers, as fully disclosed in the previously mentioned Letters Patent. For thus depressing the wipers the carrier 166 is provided with a screw 170 the head of which is arranged to engage the top of the plunger 156, and also with arms 172, one of which is shown in Fig. 2, arranged to engage the wipers 22 in locations over the plungers 160. The depression of the wipers relatively to the shoe is limited by contact of a presser foot 174 supported on the carrier 166 with the bottom face of the heel end of the insole. In order to tip the wipers laterally of the shoe to position them in a plane substantially parallel to the lateral slope of the bottom face of the heel end of the last, as hereinbefore described, the arms 172 and the presser foot 174 are not mounted directly on the carrier 166, but on a holder 176 which may rock or tip relatively to the carrier laterally of the shoe. Provision for such tipping of the holder 176 is afforded by means more fully disclosed in Letters Patent No. 1,979,269, comprising curved slots in the holder and rolls supported on the carrier 166 and lying in these slots, one of the slots being shown at 178 and one of the rolls at 180 in Fig. 1. It will be understood that by such tipping movement the holder 176 assumes a position determined by contact of the presser foot 174 with the heel end of the insole, and that by engagement of its arms 172 with the wipers it positions the wipers at a lateral inclination determined by such contact of the presser foot with the insole.

Since the area of the insole-engaging face of the presser foot 174 is necessarily rather small in order that the presser foot may be out of the way of the heel wipers in wiping the upper over the insole, it is desirable that there be as little resistance as possible to the tipping of the holder 176 and the wipers. Accordingly, as herein shown the plungers 160 are controlled by means so constructed as to oppose substantially no resistance to such relative vertical movements of the plungers as result from the tipping of the wipers. By reference to Fig. 7 it will be seen that the reduced lower ends of the plungers 160 extend downwardly from the levers 102 and are supported on the opposite arms of a lever 182 which is pivotally mounted at 184, midway between its opposite ends and midway between the points where the plungers engage it, on a slide 186 vertically movable in guideways in the slide 26. A spring 188 supported on a bracket 190 on the slide 26 supports the slide 186 and the lever 182, the upward movement of this slide being limited by a screw 192 mounted in the slide 26 and extending into a slot 193 in the slide 186. It will thus be seen that the lever 182

182 is movable bodily downward against the resistance of the spring 183 in response to pressure of both plungers 160 thereon when the plungers are depressed by the downward movement of the 5 wipers prior to the limiting engagement of the presser foot 174 with the insole, but that there is no resistance other than the negligible friction between parts of the mechanism to such relative movements of the plungers as result from tipping 10 of the wipers laterally of the shoe. When either 15 of the plungers is depressed by the tipping of the wipers, the other plunger is lifted a corresponding distance by the equalizing action of the freely movable lever 182. The mechanism provided accordingly facilitates the positioning of the wipers in proper relation to the plane of the heel end of the last bottom.

The previously mentioned toe-lasting mechanism includes, as heretofore, a slide 194 (Figs. 1 20 and 11) adjustable in directions lengthwise of the shoe along guideways on the frame of the machine. On the slide 194 is supported a casting 196 adjustable about an axis extending laterally 25 of the shoe along curved guideways 198. This casting supports means for wiping the upper upwardly about the toe-end portion of the last as the last is forced downwardly by the previously mentioned presser foot 174 and by other means, hereinafter more particularly referred to, which 30 engages the toe end of the insole. For thus wiping the upper upwardly, in the construction herein shown, there is fast on the casting 196 a block 200 which supports a pair of levers 202 (Figs. 11 and 15) pivotally mounted between their ends on 35 pins 204 on the block for swinging movements in directions widthwise of the shoe. The inner arms of these levers, i. e., the arms nearer the shoe, carry upwardly extending pins 206 which serve as pivotal supports for blocks 208 (Fig. 14) having 40 slots therein to receive the end portions of a flexible upwiping and clamping band 210. Supported on the upper face of the block 200 are a plurality of small slides 212 which extend in a series between the two blocks 208, these slides also having 45 slots therein to receive the band 210. The slides 212 are bodily movable relatively to one another inwardly or outwardly along the supporting face of the block 200 in directions substantially radial to the curve of the edge of the shoe bottom. Ex- 50 tending around the series of slides 212 and located in recesses in the slides is a coiled spring 214 the opposite ends of which are connected to pins 216 mounted on lugs on the inner ends of the levers 202. The spring 214 thus tends to move 55 the several slides 212 inwardly toward the shoe and is yieldable to permit the slides to be forced in outward directions by wedging action of the shoe on the band 210 as the toe end of the last is forced downwardly within the band. The slides 60 212 which are located around the extreme end of the toe are confined on the upper face of the block 200 by a plate 218 which overlies outwardly projecting fingers 220 on the slides, as illustrated in Figs. 11 and 14. Inward movements of the 65 slides which are thus confined by the plate 218 are limited by a curved rib 222 (Fig. 15) extending upwardly from the block 200. Two of the slides 212 at each end of the series, the inward movements of which are not limited by the rib 222, have thereon upwardly extending pins 224 70 arranged to engage the spring 214 to insure against undue displacement of these slides if the band 210 is removed.

The band-supporting end blocks 208 also are 75 yieldingly controlled to permit them to be forced

apart by wedging action of the shoe on the band. For this purpose the outer arm of each lever 202 has rotatably mounted therein a stud 226 (Figs. 11 and 15) provided below the arm with a block 228 to receive a transverse rod 5 230, the end of this rod being threaded in one of the blocks 228 and its intermediate portion being swiveled in the other block. A spring 232 mounted on this rod between the last-mentioned block and a collar 234 which is fast on the rod 10 tends to swing the inner band-supporting arms of the levers 202 inwardly toward each other and is yieldable to permit these arms to be forced apart by wedging action of the shoe on the band. Inward movements of the band-supporting 15 arms of the levers are limited by a collar 236 fast on the rod 230 and engaging one of the blocks 228. It will be evident that by turning the rod 230 through a hand wheel 238 thereon the band-supporting arms of the levers may be adjusted toward or from each other for shoes of different widths. The band 210 is not secured to the blocks 208 and the slides 212, but simply rests in the slots provided in these parts to receive it, so that the band may slide more or 20 less in directions lengthwise of its edge in some of the slots as different portions of the band are wedged outwardly by the shoe. It will thus be seen that the band is controlled in such manner that it may readily yield outward in all directions as the toe end of the shoe is forced downwardly within it, while engaging the upper frictionally with pressure resulting from the action of the springs 214 and 232 to effect the upwiping 25 operation. 35

To insure that the band 210 will wipe the upper effectively upward as far as the edge of the insole in operating on shoes made on lasts of different styles, the band is so formed that it flares outwardly from the shoe in a downward 40 direction, and accordingly it is only the upper edge portion of the band that actually contacts with the upper, as illustrated in Figs. 21 and 22. It will be understood that the band first engages the upper in a location at a substantial 45 distance below the edge of the insole while in a comparatively contracted condition, as shown in Fig. 21, and that it is wedged outwardly both lengthwise and laterally of the shoe as the shoe is forced downwardly within it. To receive the 50 outwardly flaring band the slots in the blocks 208 and the slides 212 are outwardly inclined, and it will be evident that this construction assists in insuring against displacement of the band by frictional action of the shoe thereon when the 55 shoe is moved upwardly after the lasting operation. As further insurance against such displacement each of the blocks 208 carries a pin 239 (Fig. 11) extending through a slot 240 in the band. The invention further provides a band 60 so constructed as to insure against deformity of its shoe-engaging edge portion in long continued use, so that the same band may be used indefinitely with equally effective results. As illustrated, the band is formed of two layers or 65 strips of material 241 and 242, the outer layer 241 being preferably formed of leather and the inner layer 242 of celluloid. The two layers 241 and 242 are secured together preferably by cement. The inner layer 242 of celluloid is suf- 70 ficiently firm to engage the upper with effective pressure and to maintain its shape against distortion or wear in long continued use, and is yet flexible enough to conform effectively to the contour of the shoe and last. The outer layer 75

241 of leather reenforces the celluloid layer and affords effective insurance against breakage of the latter.

Substantially as disclosed in the previously mentioned Letters Patent, the toe end of the shoe, as it is depressed within the toe band 210, is engaged on its top face by means which acts frictionally to pull the upper forwardly toward the end of the toe. This means comprises a toe rest 244 (Fig. 11) fast on a hollow plunger 246 which is slidably mounted in a holder 248 and is depressible by the shoe against the resistance of a spring 250. The holder 248 is pivoted at 252 on the casting 196 for swinging movement against the resistance of a spring-controlled plunger 254 to carry the toe rest forwardly, such swinging movement being effected in response to depression of the plunger 246. For this purpose the plunger carries a roll 256 which is engaged by a cam member 258 as the plunger is depressed. In the construction herein shown the cam member 258 is pivoted at 260 for adjustment to vary the amount of upper-pulling movement thus imparted to the toe rest 244. Adjustment of the member 258 is effected by a screw 262 against the end of which the member is held by a spring 264.

The previously mentioned toe wipers for wiping the marginal portion of the upper inwardly over the insole around the toe end of the last after the upwiping operation, and the means for operating these wipers are generally similar to the disclosure of the previously mentioned Letters Patent, but differ therefrom in certain respects. These wipers comprise a pair of end wiper plates 266 (Figs. 10 and 12) for wiping the upper inwardly around the end and along the sides of the toe and a pair of side wiper plates 268 for wiping the upper inwardly at the sides only of the toe. The plates 268 are comparatively thin plates which are fast on arms 270 pivoted at 272 on the casting 196 for swinging movements laterally of the shoe about axes extending heightwise of the shoe. The plates 266 are connected together by a pin 274 for swinging movements toward and from each other widthwise of the shoe, and in operation they are also advanced bodily lengthwise of the shoe relatively to the side plates 268 with portions of them overlapping these side plates, as will be evident by comparison of Figs. 10 and 12. The end plates 266 are supported on a bracket 276 (Fig. 11) secured by a screw 278 to a carrier 280, and these plates carry pins 282 (Figs. 10 and 12) which extend into slots 284 formed in the carrier 280 concentric with the axis of the pin 274. The outer edges of the portions of the plates 266 which rest on the bracket 276 are also concentric with the axis of the pin 274 and engage similarly curved surfaces on the bracket, as indicated at 286 (Fig. 10). The carrier 280 is supported on a rack bar 288 (Fig. 11) which is movable in guideways in the casting 196 and is engaged by a gear sector 290 fast on a rock shaft 292 for imparting movement lengthwise of the shoe to the wiper plates 268. Provision is afforded for relative movement lengthwise of the shoe of the carrier 280 and the rack bar 288 within limits determined by a screw 294 which is threaded in the rack bar and lies in a slot 296 in the carrier 280. A spring 298 located between the rack bar 288 and the bracket 276 on the carrier 280 positions the carrier normally in the relation to the rack bar illustrated in Fig. 11 but is yieldable in response to any abnormal resistance to the ad-

vancing movement of the wiper plates 266. These wiper plates and also the side wiper plates 268 are closed laterally of the shoe by rack bars 300 (Fig. 10) slidably movable in the casting 196 and operated as disclosed in the previously mentioned Letters Patent by the rock shaft 292. These rack bars are adjustably connected to slides 301 which are connected by links 302 to levers 304 pivoted at 306 on the casting 196, these levers being provided with pins 308 for closing the 10 wiper plates 266 through links 310 which are pivotally connected to these plates. The levers 304 serve also to operate the side wiper plates 268 through swinging movements of the arms 270, the connections between each lever 304 and the 15 arm 270 associated therewith, in the construction herein shown, comprising a slide 312 (Fig. 16) which is mounted in a dovetailed guideway in the arm 270 and is fastened in a slot in the lever 304 by a depending portion of the previously 20 mentioned pin 308. As illustrated in Fig. 10, the side wiper plates 268 are positioned initially far enough apart to allow ample room between them for shoes of different widths, and in order to delay the beginning of the closing movements of the end wiper plates 266 until the side plates have been moved into substantially as close relation to the shoe as the end plates, the links 310 are provided with slots 314 in which the pins 308 operate.

For laying the margin of the upper inwardly over the insole in locations immediately beyond the ends of the side wiper plates 268, there is associated with each of these plates, in the construction herein shown, a pair of rolls 316 (Figs. 35 9, 10, 11 and 12). Each pair of rolls is rotatably mounted on a pin 318 fast on a holder 320 provided with a cylindrical stem extending within a recess in an arm 322. The arm 322 is pivotally mounted for swinging movements heightwise of the shoe on a pin 324 (Fig. 10) which projects laterally from a lug 326 on the arm 270 which carries the wiper plate 268. A spring 328 (Fig. 11) underlying a lug 330 which projects from the arm 322 tends to swing the arm in the 40 direction to depress the rolls 316, such swinging movement of the arm being limited by its engagement with a portion of the wiper plate 268. The stem which projects from the holder 320 into the arm 322 is rotatable in the arm and carries a 50 pin 332 (Fig. 9) projecting into a slot 334 in the arm to retain the holder 320 in place on the arm while permitting limited turning movement of the holder such that the rolls 316 may adjust themselves to the lengthwise contour of the shoe 55 bottom. It will be noted that initially the rolls 316 extend downwardly a little farther than the wiper plates 268, and as they are moved inwardly they first contact with the toe band 210 and are deflected or lifted thereby to the level of the 60 shoe bottom, the band extending along the sides of portions of the shoe where the rolls operate. The rolls are also positioned nearer the shoe than the edges of the plates 268 so that they begin to lay the upper inwardly over the insole before the 65 plates 268 begin to wipe the upper inwardly. This assists in insuring against any undue displacement of the margin of the upper lengthwise of the shoe by the wiper plates. The rolls 316 serve not only to lay the margin of the upper 70 over the insole in the locations where they operate, but also assist in insuring that the margin of the insole will be pressed close against the bottom of the last so as not to be displaced by the wiper plates 268. The portion of each holder 75

320 which is between the rolls 316 is flush with the peripheries of the rolls so as to avoid any creasing of the upper by the rolls.

Cooperating with the heel presser foot 174 to effect the depression of the last and shoe is another presser foot 336 (Fig. 17) which engages the toe end of the insole, this presser foot being mounted on a bracket 337 adjustable as hereinabove described on an arm 338 supported by aligned posts 340 and 342 (Fig. 1) which are mounted for vertical movements and for turning movements in bearings in the frame of the machine. The arm 338 occupies initially, as heretofore, a position in which the presser foot 336 is retracted 10 rearwardly from over the shoe bottom, and the operator swings the arm forwardly to position the presser foot over the shoe bottom by use of a handle 344 on the arm, the posts 340 and 342 turning in their bearings in the frame. Thereafter 15 in the power operation of the machine the arm is carried downwardly to bring the presser foot into engagement with the insole and to assist in depressing the last and shoe.

Supported on the arm 338 in the construction herein shown is novel means for engaging the insole around the presser foot 336 to insure that the margin of the toe end of the insole will lie close to the bottom of the last in the overwiping operation and for also engaging the marginal portion of the upper around the toe end to assist the toe wipers in wiping the upper tightly and smoothly over the insole without any objectionable wrinkles. This means comprises a clamping device 346 (Figs. 17 and 19) which engages the insole initially close to the presser foot 336 and thereafter receives outward movement toward the edge of the insole while in contact with the insole. The clamping device 346 comprises a curved end member 350 and two side members or arms 352 which are pivotally connected by studs 354 to the end member 350 for swinging movements laterally of the shoe. The clamping device is supported on a pair of crossed levers 356 (Figs. 17, 18 and 20) which extend generally lengthwise of the shoe and are pivotally connected together and to the forward end of a carrier 358 by a pin 360. Rotatably mounted in the forward end of each lever 356 is a stud 362 which extends below the lever and carries a transverse stud 364 on which one of the arms 352 is pivoted for swinging movements in directions heightwise of the shoe. It will thus be seen that the clamping device 346 can swing heightwise of the shoe about the axes of the studs 364 and that the two arms 352 may be swung toward or from each other about the axes of the studs 354 by swinging movements of the levers 356. A spring 366 the lower end of which is positioned by a pin 368 on the member 350 and the upper end of which is seated in a recess in the pivot pin 360 tends to swing the clamping device 346 downwardly, its downward movement being limited by contact of the ends of the arms 352 with the levers 356, as illustrated in Fig. 17. When the supporting arm 338 receives its downward movement the member 350 accordingly first engages the insole, whereupon the spring 366 yields until this member and the members 352 are seated upon the insole in parallel relation to the bottom of the last.

The carrier 358 on which the crossed levers 356 are mounted as above described is pivotally supported at its left-hand end (Fig. 17) on a rod 370 which extends through a bearing in the carrier and is itself mounted in the lower ends of a pair of swinging links 372 and 374 which are pivoted

at or near their upper ends on the arm 338 at opposite sides of the arm. This permits the arm 338 to continue its downward movement, after the clamping members 350 and 352 have seated themselves upon the insole, to bring the presser foot 336 into contact with the insole. Such further downward movement of the arm relatively to the members 350 and 352 is effected against the resistance of a spring 376 (Fig. 20) which is mounted in the arm and controls a plunger 378 connected by a link 380 to the carrier 358. The spring 376 engages the head of a screw 382 which is threaded in the plunger 378, the head of the screw being of greater diameter than the plunger and engaging a shoulder on the arm to limit downward movement of the plunger. It will thus be seen that the clamping device 346 is pressed yieldingly upon the insole through the spring 376 and the previously mentioned spring 366 and it is maintained in such yielding engagement with the insole during the depression of the last and shoe. At this time the member 350 and the arms 352 of the clamping device are located comparatively close to the presser foot 336. At the beginning of the operative movement of the toe wipers, after the depression of the last and shoe, the clamping device is moved bodily forward or outward toward the end of the toe while in contact with the insole and the arms 352 are swung outward toward the side edges of the insole to insure that the margin of the insole around the toe will lie smooth upon the bottom of the last and also to position the device to serve as a retarder or spreader in engagement with the margin of the upper at the edges of the wipers. Such bodily forward movement of the clamping device is effected by moving its carrier 358 toward the left (Figs. 17 and 18) accompanied by swinging movements of the links 372, 374 and 380 which support the carrier, and for this purpose the rod 370 on which the left-hand end of the carrier is supported is moved toward the left by means hereinafter described which engages a roll 394 on the rod. This movement is against the resistance of a spring 386 connected at one end to a pin 388 on the arm 338 and at its other end to a portion of the link 374 which extends upwardly beyond the pivotal connection of the link with the arm. This upwardly extending portion of the link 374 by contact with the pin 388 determines the initial position of the clamping device 346 lengthwise of the shoe. As the carrier 358 is thus moved toward the left, the arms 352 of the clamping device are swung outwardly away from each other by movements of the crossed levers 356 about the pivot pin 360. For this purpose there is provided a cam block 390 (Fig. 17) having thereon cam faces 392 (Fig. 18) arranged to engage rolls 394 on the left-hand ends of the levers 356 as the carrier 358 is moved toward the left as above described. Such swinging movements of the levers 356 is effected against the resistance of a spring 396 which is mounted on a stud 398 on one of the levers and bears on the side of the other lever. It will be understood that through the action of this spring the rolls 394 are held initially in contact with the sides of the carrier 358. The cam block 390 is fastened by screws 400 to a member 402 which partially overlies the carrier 358, this member having a forked end 404 partially embracing a pin 406 on the arm 338 to hold the cam block 390 against movement to the left or right with the carrier 358 while permitting it to swing upwardly or downwardly with the carrier. In the outward swinging movements of

the arms 352 their insole-engaging portions arrive approximately at the edge of the insole at the time when the corresponding portion of the member 350 arrives in a similar position, as illustrated in Fig. 22, at which time the wipers 266 in their advancing movement arrive substantially at the edge of the insole. At this point in the operation of the machine the marginal portion of the upper becomes yieldingly clamped between the edges of the wipers and outwardly inclined wedge faces of the members 350 and 352. Thereafter, as the wipers are further advanced and as they are closed to wipe the margin of the upper over the insole, the members 350 and 352 act as retarders or spreaders, maintaining the margin of the upper substantially free from wrinkles as it is wiped inwardly by the wipers and rendering the wipers more effective to wipe the upper tightly over the insole. It will be understood that in this operation the members 350 and 352 are wedged upwardly away from the insole against the resistance of the springs 366 and 376 by the action of the wipers on their inclined faces. The outward movements of the members 350 and 352 may continue somewhat beyond the point in the cycle of operations represented by Fig. 22, depending upon the adjustment of the operating means hereinafter described.

As the arm 338 receives its downward movement and carries the clamping device 346 into engagement with the insole as above described, it carries another clamping device into position to clamp the margin of the upper outspread upon the wiper plates 266, as illustrated in Fig. 21, this device comprising a clamp member 407 which is curved similarly to the edges of the plates 266. Accordingly, as the last is thereafter depressed by further downward movement of the arm 338, the clamp member 407 cooperates with the wipers to apply to the toe portion of the upper an upward pull as it is being wiped upwardly by the toe band 210, the margin of the upper slipping more or less between the clamp member and the wipers in this operation. The clamp member 407 is supported by links 408 and 410 (Figs. 17, 18 and 19) located respectively at opposite sides of the arm 338, the link 408 being pivotally supported on a lever 412 and the link 410 on a lever 414 (Fig. 20). These levers are fast at their left-hand ends on a rockshaft 416 mounted in the arm 338. At their lower ends the links 408 and 410 have curved segmental portions provided with guideways to receive curved flanges 418 (Fig. 19) on the member 407 so that this member may rock about an axis extending laterally of the shoe and thus seat itself evenly upon the upper overlying the wipers. The heads of screws 420 which are threaded in the links 408 and 410 are arranged to contact with shoulders 422 (Figs. 21 and 22) on the member 407 to limit its rocking movement in one direction, while rocking movement thereof in the other direction is limited by contact of portions of the member with the links. To determine adjustably the normal position of the member 407 heightwise of the shoe relatively to the clamping device 346, there is threaded in a lug on the lever 412 a screw 424 the lower end of which is arranged to engage a lug 426 on the arm 338. To hold the member 407 yieldingly in clamping engagement with the upper there is provided in the handle 344 a spring 428 which bears on a plunger 430 connected by a link 432 to the lever 412. It will be understood that this spring yields after the member 407 has arrived in clamping engagement with the upper as the arm

338 continues its downward movement to depress the last and shoe.

The initial position of the clamp member 407 lengthwise of the shoe is adjustably determined by means associated with the link 410. This means comprises a rod 434 (Figs. 17 and 20) pivotally mounted on a pin 436 on the arm 338 and extending through a vertical slot 438 (Fig. 17) in the link 410, the rod having mounted thereon a spring 440 which at one end engages a collar 442 fast on the rod and at the other end engages a washer 444 slidably mounted on the rod and having a curved face for engaging the link 410. On the opposite side of the link is another similar washer 446 positioned adjustably by nuts 448 on the end of the rod 434. It will thus be seen that the link 410 is held yieldingly against the washer 446 by the spring 440, and that the position of the member 407 lengthwise of the shoe is thereby determined. It may be necessary under some conditions to impart to this clamp member a short forward movement to make way for the forwardly moving clamping device 346, and for this purpose there are connected respectively to the links 408 and 410 substantially horizontal links 450 and 452 (Figs. 17 and 18), these links having slots 454 and 456 therein through which extends the previously mentioned rod 370. These slots afford provision for lost motion between the rod 370 and the links 450 and 452, so that when the rod is moved toward the left in the manner hereinbefore described to impart to the clamping device 346 its forward movement, it does not ordinarily act on the links 450 and 452 until this clamping device has received at least the greater portion of its forward movement. It will be understood that the margin of the upper slips out from under the clamp member 407 as the wipers wipe the upper inwardly over the insole, the members 350 and 352 acting as hereinbefore described on portions of the margin previously engaged by this clamp member.

For operating the roll 384 to move the rod 370 to the left and thereby impart to the clamping devices 346 and 407 their forward movements, there is provided mechanism which is operated by the means hereinbefore described for imparting closing movements to the toe wipers. This mechanism comprises a bar 458 (Fig. 9) slidably movable in directions lengthwise of the shoe on a cover plate 460 above the toe wipers and guided between pins 462 on the cover plate, the bar having an upwardly extending finger 464 into operative relation to which the roll 384 is carried by the downward movement of the arm 338. The bar 458 is pivotally connected to a lever 465 which is pivotally mounted on a pin 466 supported by a bracket 468 fast on the cover plate 460, and pivoted on the same pin is a lever 470 which carries a screw 472 arranged to engage and operate the lever 465. A spring-pressed plunger 474 in the bracket 468 engages the lever 465 on the opposite side from the screw to hold the lever against the screw and to return it to its initial position when permitted. The lever 470 carries a roll 476 which is engaged and operated by a cam piece 478 adjustably secured to one of the slides 301 through which closing movements are imparted to the toe wipers, this cam piece operating in a slot 480 in the cover plate 460. It will be observed that the cam piece 478 is so formed and arranged as to swing the lever 470 for the purpose described at the beginning of the operative movements of the slides 301 as the side wiper plates 268 are swung inwardly toward the shoe.

relatively to the end wiper plates 266, and later the roll 476 is engaged by the straight side of the cam piece and the lever 470 receives no further movement during further wiper-closing movements of the slides 301. That face of the finger 464 which engages the roll 384 is curved in such manner relatively to the axis of adjustment of the wiper-supporting casting 196 along the guideways 198 that the operative relation of the finger to the roll is substantially unaffected by adjustment of the casting. By the screw 472 the arm 465 may be adjusted to vary the time when the finger 464 begins to operate on the roll 384 and thereby to vary the amount of movement imparted to the clamping devices 346 and 407.

15 The previously mentioned bracket 337 (Fig. 17) supporting the toe presser foot 336 is adjustable heightwise of the shoe relatively to its supporting arm 338 along guideways provided on the arm and is held in adjusted position by a screw 482 threaded in a lug 484 on the arm and provided with an annular recess near its lower end in which lies the forked end of a plate 486 fast on the bracket 337. By this means the position to which the toe end of the shoe is depressed by the presser foot 336 may be adjustably determined.

20 The machine herein shown is further provided with means similar to that disclosed in Letters Patent No. 1,979,269 for positioning the toe end of the last and shoe laterally when the work is presented to the machine. This means comprises gage members 488 (Fig. 9) positioned over the toe wipers 266 and arranged to contact with the upper at the opposite sides of the toe, these members being mounted on bell-crank levers 490 which are pivoted on the cover plate 460 and are connected together by gear sectors 492 for equalized swinging movements to carry the gage members toward and from each other. The members 488 in the constructions herein shown are fast on the levers 490. A spring 494 connected to one of the levers 490 and to a bracket 496 tends to swing the levers 490 in directions to separate the gage members 488 from each other. Such movement of the levers is adjustably limited by the end of a spindle 498 in contact with one of the levers, this spindle being threaded in a nut 500 which is slidably mounted in a socket in the bracket 496 and is backed up by a spring 502. A pin 504 in the bracket 496 lies in a slot in one side of the nut 500 to limit movement of the nut and the spindle 498 under the influence of the spring 502 and also to prevent the nut from turning. It will thus be evident that adjustment of the gage members 488 is effected by turning the spindle 498 relatively to the nut 500, and also that the gage members may be forced apart by pressure upon them against the resistance of the spring 502, the nut 500 and the spindle 498 being forced outward through the action of one of the levers 490 on the spindle. The gage members will preferably be so adjusted that when the operator presents the work to the machine, mounting the last on the last pin 2, these members will be forced somewhat apart by pressure of the shoe against them, so that when the shoe is moved lengthwise as hereinbefore described to seat its heel-end face against the heel band, the gage members will maintain contact with the shoe.

70 The machine herein shown is provided with means for withdrawing the gage members 488 from their operative positions so that they will not interfere with the clamping of the margin of the upper outspread on the toe wipers by the member 407 as hereinbefore described. For this

purpose the bracket 496 is mounted to swing about the same pivot stud 506 as the bell-crank lever 490 which is adjacent to the bracket, a screw 508 projecting from the cover plate 460 through a slot 510 in the bracket being provided to assist in controlling it. The withdrawal of the gage members is effected by swinging movement of the bracket 496 in a clockwise direction (Fig. 9), the spring 494 swinging the gage-supporting arms of the bell-crank levers 490 apart as the bracket 10 receives such swinging movement. The swinging of the bracket 496 in this manner is effected by the swinging of the shoe-depressing arm 338 (Fig. 1) from its idle position to its position over the toe end of the shoe. As disclosed in the previously mentioned Letters Patent, such swinging movement of the arm 338 is availed of to start the power operation of the machine. For this purpose there is mounted on the previously mentioned post 342 a collar 512 (Figs. 9 and 13) which turns with the post and by its turning movement imparts lengthwise movement to a rod 514 extending loosely through an opening in a thimble 516 in the frame. Mounted on the rod 514 is a spring 518 which is compressed by the turning 15 of the collar 512 and serves later to return the arm 338 to its initial position. When the rod 514 is thus moved lengthwise by the swinging of the arm 338 to its position over the shoe, it acts as heretofore on a bell-crank lever 520 (Fig. 13) to 20 lift a link 522 and thus to trip the clutch (not shown) through which the machine is operated. The rod 514 thus operates the bell-crank lever 520 through a swinging arm 524 which is interposed between the end of the rod and a screw 35 526 mounted in one arm of the bell-crank lever. The arm 524 is fast on a rockshaft 528, and for the purpose of withdrawing the gage members 488 from their operative positions there is also fast on this rockshaft, as herein shown, an upwardly extending arm 530. Swiveled on the upper end of the arm 530 is a collar 532 slidably mounted on a rod 534 between a collar 536 which is fast on the rod and a spring 538 which is mounted on the rod in engagement with a collar 540 40 also fast on the rod. The rod 534 is pivotally connected to one arm of a latch 542 (Fig. 9) which is pivoted at 544 on one arm of a bell-crank lever 546 pivoted on the cover plate 460, the other arm of this bell-crank lever being forked for engagement with a pin 548 on the previously mentioned swinging bracket 496. A spring 550 connected to the bell-crank lever 546 and to a pin 552 on the cover plate 460 acts normally through the bell-crank lever to maintain the bracket 496 at a 45 limit of movement determined by the screw 508 and the slot 510, as illustrated in Fig. 9. With the parts in these positions, the latch 542 is in engagement with the pin 552 to prevent positively any swinging of the bracket 496 by pressure applied to the gage members 488. When the arm 338 is swung forwardly over the shoe the arm 530 acts through the spring 538 to push the rod 534 in a forward direction, the first effect of which is to swing the latch 542 to a position determined by 50 a stop pin 554 on the bell-crank lever 546 and thus to disconnect the latch from the pin 552. In its further movement the rod 534 then acts through the latch to swing the bell-crank lever 546 against the resistance of the spring 550 and thereby to swing the bracket 496 in the direction to withdraw the gage members 488 from their operative positions over the wipers 266 into notches 556 in the cover plate 460. The gage members are thereafter maintained in their inoperative 55

positions until the arm 338 is swung rearwardly near the end of the cycle of the machine, whereupon the bell-crank lever 546 and the bracket 496 are returned to their initial positions by the 5 spring 550 and the latch 542 is returned into locking relation to the pin 552 by return movement of the rod 534. Such movement of the rod is effected by action of the arm 530 on the collar 536 on the rod, the arm 530 receiving its return 10 movement through the bell-crank lever 520 from a spring (not shown) controlling this lever.

Since the manner of operation of the novel mechanisms provided by the invention has been explained in connection with the description of 15 these mechanisms, no further description of the operation of the machine is necessary.

Having described the invention, what I claim as new and desire to secure by Letters Patent of the United States is:

20 1. In a lasting machine, the combination with toe-lasting mechanism, of a support for a last and shoe movable in directions lengthwise of the shoe, clamping means arranged to engage the heel-end face of the shoe and to determine by 25 such engagement the position of the toe-end face of the last relatively to the toe-lasting mechanism, a spring for moving said support to carry the last and shoe toward said clamping means, and mechanism for holding said support initially 30 retracted against the resistance of said spring and for releasing it to the action of the spring.

2. In a lasting machine, the combination with toe-lasting mechanism, of a support for a last and shoe movable in directions lengthwise of the 35 shoe, clamping means arranged to engage the heel-end face of the shoe and to determine by such engagement the position of the toe-end face of the last relatively to the toe-lasting mechanism, said clamping means being movable lengthwise of the shoe toward its heel end, means for limiting such movement of the clamping means, and automatic means for imparting to said shoe support movement to carry the heel-end face of the shoe into engagement with said clamping means 40 when the latter has substantially arrived at the limit of its movement.

3. In a lasting machine, the combination with toe-lasting mechanism, of a support for a last and shoe movable in directions lengthwise of the 45 shoe, clamping means arranged to engage the heel-end face of the shoe and to determine by such engagement the position of the toe-end face of the last relatively to the toe-lasting mechanism, said clamping means being movable lengthwise of the shoe toward its heel end, means for limiting such movement of the clamping means, and mechanism controlled by said clamping means for imparting to said shoe support movement to carry the heel-end face of the shoe into 50 engagement with the clamping means.

4. In a lasting machine, the combination with toe-lasting mechanism, of a support for a last and shoe movable in directions lengthwise of the shoe, clamping means arranged to engage the heel-end face of the shoe and to determine by such engagement the position of the toe-end face of the last relatively to the toe-lasting mechanism, said clamping means being movable lengthwise of the shoe toward its heel end, means for limiting such movement of the clamping means, a spring for moving said shoe support to carry the last and shoe toward the clamping means, a latch arranged to hold the shoe support initially retracted against the resistance of said spring and movable to release it to the action of the spring, and mechanism arranged to be operated by movement of said clamping means away from the shoe to return the shoe support into position to be held by said latch.

5. In a lasting machine, the combination with toe-lasting mechanism, of a support for a last and shoe movable in directions lengthwise of the shoe, clamping means arranged to engage the heel-end face of the shoe and to determine by such engagement the position of the toe-end face of the last relatively to the toe-lasting mechanism, said clamping means being movable lengthwise of the shoe toward its heel end, a spring arranged to be released to move said clamping means toward the shoe, and another spring controlling said shoe support and arranged to be released by the movement of the clamping means toward the shoe to cause it to impart to said support movement to carry the shoe toward the clamping means.

6. In a lasting machine, the combination with toe-lasting mechanism, of a support for a last and shoe movable in directions lengthwise of the shoe and including a last pin for engaging the heel end of the last in its spindle hole, means for clamping the shoe about its heel end arranged to determine by contact with the heel-end face of the shoe the position of the toe-end face of the last relatively to the toe-lasting mechanism regardless of the position of the spindle hole in the last, said clamping means being movable lengthwise of the shoe toward its heel end, means for limiting such movement of the clamping means, and mechanism for imparting automatically to said shoe support movement to carry the shoe toward said clamping means when the latter has substantially arrived at the limit of its movement.

7. In a lasting machine, the combination with toe-lasting mechanism, of a support for a last and shoe movable in directions lengthwise of the shoe, clamping means arranged to engage the heel-end face of the shoe and to determine by such engagement the position of the toe-end face of the last relatively to the toe-lasting mechanism, said clamping means being movable lengthwise of the shoe toward its heel end, means for limiting such movement of the clamping means, means for imparting to said shoe support movement to carry the shoe toward said clamping means, and mechanism arranged to be operated by movement of the clamping means away from the shoe to return the shoe support to its initial position.

8. In a lasting machine, the combination with toe-lasting mechanism, of a support for a last and shoe movable in directions lengthwise of the shoe, clamping means arranged to engage the heel-end face of the shoe and to determine by such engagement the position of the toe-end face of the last relatively to the toe-lasting mechanism, said clamping mean being movable lengthwise of the shoe toward its heel end, means for limiting such movement of the clamping means, a spring for moving said shoe support to carry the last and shoe toward the clamping means, a latch arranged to hold the shoe support initially retracted against the resistance of said spring and movable to release it to the action of the spring, and mechanism arranged to be operated by movement of said clamping means away from the shoe to return the shoe support into position to be held by said latch.

9. In a lasting machine, a support for a last and shoe movable in directions lengthwise of the shoe, a device movable lengthwise of the shoe toward its heel end to a predetermined position and arranged to determine the lengthwise position of the shoe by contact with its heel-end face, and automatic means for moving said shoe

support to carry the heel-end face of the shoe into contact with said device when the latter has substantially arrived at the limit of its movement toward the shoe.

5 10. In a lasting machine, a support for a last and shoe movable in directions lengthwise of the shoe, a device movable lengthwise of the shoe toward its heel end to a predetermined position and arranged to determine the lengthwise position of the shoe by contact with its heel-end face, and a spring arranged to be released by the movement of said device toward the shoe and to impart to the shoe support movement to carry the heel-end face of the shoe into contact with said device.

15 11. In a lasting machine, a support for a last and shoe movable in directions lengthwise of the shoe and including a last pin for engaging the heel end of the last in its spindle hole, heel-lasting mechanism comprising a heel band and wipers, a slide supporting said heel-lasting mechanism and movable to carry said mechanism lengthwise of the shoe toward its heel end, means for limiting such movement of the slide, and 20 automatic means for operating said shoe support to carry the shoe toward the heel band when said slide has substantially arrived at the limit of its movement.

25 12. In a lasting machine, a support for a last and shoe movable in directions lengthwise of the shoe and including a last pin for engaging the heel end of the last in its spindle hole, heel-lasting mechanism comprising a heel band and wipers, a slide supporting said heel-lasting mechanism and movable to carry said mechanism lengthwise of the shoe toward its heel end, means for limiting such movement of the slide, a spring for moving said shoe support in the direction to carry the shoe toward the heel band, 30 and a latch arranged to hold said support initially retracted against the resistance of said spring and to be operated by the movement of said slide to release the support to the action of the spring.

35 13. In a lasting machine, a support for a last and shoe movable in directions lengthwise of the shoe and including a last pin for engaging the heel end of the last in its spindle hole, heel-lasting mechanism comprising a heel band and wipers, a slide supporting said heel-lasting mechanism and movable to carry said mechanism lengthwise of the shoe toward its heel end, a spring for imparting such movement to the slide, means for limiting the movement of the slide, 40 and another spring arranged to be rendered operative by the movement of the slide to impart to said shoe support movement to carry the shoe toward the heel band.

45 14. In a lasting machine, a support for a last and shoe movable in directions lengthwise of the shoe and including a last pin for engaging the heel end of the last in its spindle hole, heel-lasting mechanism comprising a heel band and wipers, a slide supporting said heel-lasting mechanism and movable to carry said mechanism lengthwise of the shoe toward its heel end, a spring for moving said shoe support in the direction to carry the shoe toward the heel band, a latch arranged to hold said support initially retracted against the resistance of said spring and to be operated by the movement of said slide to release the support to the action of the spring, and mechanism arranged to be operated by reverse movement of said slide to return the shoe 50 support into position to be held by said latch.

5 15. In a lasting machine, the combination with lasting mechanism, of a support for a last and shoe including a last pin for engaging the heel end of the last in its spindle hole, said last pin being movable bodily in a curved path such as to permit lateral tipping movement of the last and shoe thereon without substantial bodily lateral displacement of the bottom of the shoe, and a stop located opposite a side face of the heel end of the last for adjustably limiting such tipping 10 of the last and shoe to position the bottom of the shoe in proper relation to the lasting mechanism.

15 16. In a lasting machine, the combination with lasting mechanism, of a support for a last and shoe including a last pin for engaging the heel end of the last in its spindle hole, said last pin being movable with the last and shoe about an axis extending lengthwise of the shoe and located approximately at the bottom of the heel end of the shoe to permit the shoe to be positioned with 20 its bottom face in proper relation to the lasting mechanism, and a stop for limiting adjustably such movement of the last pin and last by contact with a side face of the heel end of the last.

25 17. In a lasting machine, the combination with lasting mechanism, of a support for right and left lasts and shoes including a last pin for engaging the heel end of each last in its spindle hole, said last pin being movable bodily in a curved path such as to permit lateral tipping movements of 30 right and left lasts and shoes respectively in opposite directions without substantial bodily lateral displacement of the bottoms of the shoes, and opposite stops arranged to act respectively on right and left lasts, each at a side face of the 35 heel end of the last, to limit such tipping movements of the lasts and thereby position the bottoms of the shoes in proper relation to the lasting mechanism.

40 18. In a lasting machine, the combination with lasting mechanism, of a support for right and left lasts and shoes including a last pin for engaging the heel end of each last in its spindle hole, said last pin being movable with each last and shoe about an axis extending lengthwise of 45 the shoe and located approximately at the bottom of the heel end of the shoe to permit the shoe to be positioned with its bottom face in proper relation to the lasting mechanism, opposite stops arranged to act respectively on right and left lasts, 50 each at a side face of the heel end of the last, to limit such tipping movements of the last, and means for adjusting said stops simultaneously equal distances toward or from each other.

55 19. In a lasting machine, the combination with toe-lasting wipers, of a support for right and left lasts and shoes including a last pin for engaging the heel end of each last in its spindle hole, said last pin being movable bodily in a curved path such as to permit lateral tipping 60 movements of right and left lasts and shoes respectively in opposite directions without substantial bodily lateral displacement of the bottoms of the shoes to position the bottom faces of the toe ends of the shoes in substantially parallel 65 relation to the toe wipers, and stops located opposite the side faces of the heel ends of the lasts and arranged to act respectively on right and left lasts to limit such tipping movements of the lasts.

70 20. In a lasting machine, the combination with 70 a shoe support, of wipers for lasting an end of a shoe on said support, said wipers being mounted for tipping movements laterally of the shoe, means for thus tipping the wipers to position them in proper relation to the bottom of each shoe, 75

and a device arranged to support said wipers and freely movable in response to the tipping of the wipers, said device comprising relatively movable members underlying the different wipers respectively and means for raising either of said members in response to depression of the other effected by the tipping of the wipers.

21. In a lasting machine, the combination with a shoe support, of wipers for lasting an end of a shoe on said support, said wipers being mounted for tipping movements laterally of the shoe, means for thus tipping the wipers to position them in proper relation to the bottom of each shoe, and a device arranged to support said wipers and 5 freely movable in response to the tipping of the wipers, said device comprising relatively movable members underlying the different wipers respectively and a lever supporting said members and movable to raise either of them in response to 10 depression of the other effected by the tipping of the wipers.

22. In a lasting machine, the combination with a shoe support, of wipers for lasting an end of a shoe on said support, said wipers being mounted 15 for tipping movements laterally of the shoe, a wiper-controlling device arranged to tip laterally of the shoe automatically to a position determined by the bottom face of the end of the shoe and thereby to tip the wipers correspondingly to a 20 position determined by said face, members relatively movable heightwise of the shoe and underlying the different wipers respectively to assist in supporting the wipers, and equalizing means 25 controlling said members to cause them to move respectively equal distances in opposite directions as the wipers are tipped.

23. In a lasting machine, the combination with a shoe support, of wipers for lasting an end of a shoe on said support, said wipers being mounted 30 for tipping movements laterally of the shoe, a wiper-controlling device arranged to tip laterally of the shoe automatically to a position determined by the bottom face of the end of the shoe and thereby to tip the wipers correspondingly to a 35 position determined by said face, members relatively movable heightwise of the shoe and underlying the different wipers respectively to assist in supporting the wipers, and a lever supporting said members at opposite sides of its fulcrum respectively and freely movable to raise either of said 40 members in response to depression of the other member by the tipping of the wipers.

24. In a lasting machine, the combination with a shoe support, of wipers for lasting an end of a 45 shoe on said support, said wipers being mounted for tipping movements laterally of the shoe, a device arranged to engage the bottom face of the end of the shoe and mounted to tip laterally of the shoe to a position determined by said face, said device having means for engaging the wipers to tip them correspondingly, plungers relatively 50 movable heightwise of the shoe and underlying the different wipers respectively to assist in supporting them, and a lever supporting said plungers at opposite sides of its fulcrum respectively, said 55 lever being movable to raise either of the plungers in response to depression of the other plunger by the tipping of the wipers.

25. In a lasting machine, the combination with a shoe support, of wipers for lasting an end of a 60 shoe on said support, said wipers being movable bodily heightwise of the shoe and also mounted for tipping movements laterally of the shoe, a wiper-controlling device mounted for movement 65 heightwise of the shoe and also for tipping move-

ment laterally of the shoe to a position determined by engagement with the bottom face of the end of the shoe and having means for correspondingly moving said wipers, members relatively movable heightwise of the shoe and underlying the different wipers respectively to assist in supporting the wipers, and equalizing means controlling said members to cause them to move respectively equal distances in opposite directions as the wipers are tipped, said equalizing means being yieldingly movable heightwise of the shoe with the wipers.

26. In a lasting machine, the combination with a shoe support, of wipers for lasting an end of a shoe on said support, said wipers being bodily 10 de-pressible heightwise of the shoe and also mounted 15 for tipping movements laterally of the shoe, a wiper-controlling device mounted for downward movement and also for tipping movement laterally of the shoe to a position determined by engagement with the bottom face of the end of the shoe and having means for correspondingly depressing and tipping wipers, plungers relatively 20 movable heightwise of the shoe and underlying the different wipers respectively to assist in supporting the wipers, a lever supporting said 25 plungers at opposite sides of its fulcrum, respectively, said lever being movable to raise either of the plungers in response to depression of the other plunger by the tipping of the wipers, and a support for said lever yieldingly de-pressible by the action of both plungers on the lever as the wipers are depressed.

27. In a lasting machine, a shoe-end-clamping device comprising a flexible band arranged to extend around an end of a shoe to clamp the upper, 30 and a second flexible band fastened to said first-named band to contact with the upper but detachable to permit said first-named band to be used alternatively in contact with an upper.

28. In a lasting machine, a shoe-end-clamping 40 device comprising a flexible band arranged to extend around an end of a shoe to clamp the upper, a second flexible band arranged to extend around the end of the shoe between said first-named band and the shoe to contact with the upper, and snap 45 fasteners detachably securing said bands together to permit the second band to be readily removed and the first band to be used alternatively in contact with an upper.

29. In a lasting machine, a shoe-end-clamping 50 device comprising a pair of flexible leather bands detachably fastened together to permit them to be used alternatively in clamping contact with the uppers of shoes.

30. In a lasting machine, a flexible band for 55 wiping an upper around the toe end of a last heightwise of the last, said band being shaped to flare outwardly from the shoe in a direction heightwise of the shoe to present an edge portion only in contact with the upper, and a plurality of 60 members supporting said band and outwardly yieldable relatively to one another in response to pressure of the shoe on the band, said members having therein outwardly inclined slots in which the outwardly flaring band is mounted. 65

31. In a lasting machine, a flexible band for wiping an upper around the toe end of a last heightwise of the last, said band being shaped to flare outwardly from the shoe in a direction heightwise of the shoe to present an edge portion 70 only in contact with the upper, members supporting the end portions of said band, arms supporting said members and mounted for swinging movements laterally of the shoe to permit the ends of the band to be forced outwardly by pres- 75

sure of the shoe thereon, and a plurality of other members arranged to support other portions of the band and slidingly mounted to yield bodily outward in response to pressure of the shoe on the band, all said members having therein outwardly inclined slots in which the outwardly flaring band is mounted.

32. In a lasting machine, a flexible band for wiping an upper around the toe end of a last 10 heightwise of the last, said band being shaped to flare outwardly from the shoe in a direction heightwise of the shoe to present an edge portion only in contact with the upper, a plurality of members arranged to extend in a series around 15 the toe end of the shoe and supporting said band, said members being outwardly movable relatively to one another in response to pressure of the shoe on the band and having therein outwardly inclined slots in which the outwardly flaring band 20 is mounted, and a coil spring extending around the series of members to hold the band pressed yieldingly against the upper.

33. In a lasting machine, a flexible band for wiping an upper around the toe end of a last 25 heightwise of the last, members supporting the end portions of said band and mounted for swinging movements laterally of the shoe to permit the ends of the band to be forced outwardly by pressure of the shoe thereon, a spring controlling 30 both said members and yieldable as the ends of the band are thus forced outwardly, and means for adjusting said members to vary the normal distance between the ends of the band.

34. In a lasting machine, a flexible band for 35 wiping an upper around the toe end of a last heightwise of the last, arms supporting the end portions of said band and mounted for swinging movements laterally of the shoe to permit the ends of the band to be forced outwardly by pressure of the shoe thereon, and a plurality of other 40 members arranged to control other portions of the band and slidingly mounted to yield bodily outward in response to pressure of the shoe on the band.

35. In a lasting machine, a flexible band for wiping an upper around the toe end of a last heightwise of the last, a plurality of members arranged to extend in a series around the toe end of the shoe to control said band, said members being 50 mounted for bodily sliding movements relatively to one another to permit them to be forced outwardly by pressure of the shoe on the band, and a coil spring extending around the series of members and against the resistance of which the 55 members are thus outwardly movable.

36. In a lasting machine, a flexible band for wiping an upper around the toe end of a last heightwise of the last, arms supporting the end portions of said band and mounted for swinging 60 movements laterally of the shoe to permit the ends of the band to be forced outwardly by pressure of the shoe thereon, spring means against the resistance of which said arms are movable as the ends of the band are thus forced outwardly, 65 a plurality of members arranged to extend in a series around the toe end of the shoe and supporting other portions of the band, said members being slidingly mounted to permit them to be forced bodily outward by pressure of the shoe 70 on the band, and a coil spring extending around said series of members and against the resistance of which they are thus outwardly movable.

37. In a lasting machine, a flexible band for 75 embracing and clamping an upper around an end heightwise of the last, a plurality of members arranged to ex-

tend in a series around the end of the last to control said band, said members being slidingly mounted for inward and outward bodily movements relatively to one another, and a coil spring extending around the series of members to hold 5 the band pressed yieldingly against the upper.

38. In a lasting machine, a flexible band for embracing and clamping an upper around an end of a last, arms supporting the end portions of said band and mounted for swinging movements 10 laterally of the shoe, spring means controlling said arms and tending to force the ends of the band inwardly, members arranged to extend in a series around the end of the shoe for controlling other portions of the band, said members being 15 slidingly mounted for inward and outward bodily movements relatively to one another, and a coil spring extending around the series of members and tending to force them inwardly.

39. In a lasting machine, a flexible band for 20 embracing and clamping an upper around an end of a last, levers pivotally mounted between their opposite ends for swinging movements laterally of the shoe and having arms supporting the end portions of said band, a rotatable screw-threaded 25 rod connected with the other arms of said levers in different locations respectively along the rod for adjusting the levers to vary the normal distance between the ends of the band, and a spring mounted on said rod and tending to swing the 30 levers in directions to press the ends of the band against the upper, said spring being yieldable in response to pressure of the shoe on the ends of the band.

40. In a lasting machine, a flexible band for 35 embracing and clamping an upper around an end of a last, arms supporting the end portions of said band and mounted for swinging movements laterally of the shoe, a plurality of members supported independently of said arms and arranged 40 to extend in a series around the end of the shoe for controlling other portions of the band, said members being slidingly mounted for inward and outward bodily movements relatively to one another, and spring means tending to force said 45 members and the arms inwardly.

41. In a lasting machine, a flexible device for wiping an upper heightwise of a last, said device comprising a strip of celluloid arranged to contact with the upper. 50

42. In a lasting machine, a flexible device for wiping an upper heightwise of a last, said device comprising a strip of celluloid arranged to contact with the upper and another strip of different flexible material fastened to the strip of celluloid. 55

43. In a lasting machine, a flexible band for wiping an upper around the toe end of a last heightwise of the last, said band being shaped to flare outwardly from the shoe in a direction 60 heightwise of the shoe to present an edge portion only in contact with the upper and comprising a strip of celluloid for engaging the upper.

44. In a lasting machine, a flexible band for wiping an upper around the toe end of a last heightwise of the last, said band being shaped to flare outwardly from the shoe in a direction heightwise of the shoe to present an edge portion only in contact with the upper and comprising an inner layer of celluloid for engaging 70 the upper and another layer of different flexible material fastened to the layer of celluloid.

45. In a lasting machine, a flexible band for wiping an upper around the toe end of a last heightwise of the last, said band being shaped to 75

flare outwardly from the shoe in a direction heightwise of the shoe to present an edge portion only in contact with the upper and comprising an inner layer of celluloid for engaging the upper and another layer of leather cemented to the layer of celluloid.

46. In a lasting machine, a flexible band for wiping an upper around the toe end of a last heightwise of the last, said band comprising a layer of celluloid arranged to contact with the upper and another layer of different flexible material arranged to reinforce said layer of celluloid.

47. In a lasting machine, a flexible band for wiping an upper around the toe end of a last heightwise of the last, said band comprising a layer of celluloid arranged to contact with the upper and another layer of leather cemented to the outer face of said layer of celluloid.

48. In a lasting machine, a flexible band for embracing and clamping an upper around an end of a last, said band comprising a layer of celluloid next to the upper and another layer of different flexible material secured to said layer of celluloid.

49. In a lasting machine, a flexible band for embracing and clamping an upper around an end of a last, said band comprising a layer of celluloid next to the upper and another layer of leather cemented to the outer face of said layer of celluloid.

50. In a lasting machine, end-lasting mechanism comprising wipers for wiping the margin of an upper inwardly over the bottom of a last at opposite sides of an end of the last, members supporting said wipers and mounted for swinging movements each about an axis extending heightwise of the last to operate the wipers, and rolls carried by said members for laying portions of the margin of the upper inwardly over the bottom of the last.

51. In a lasting machine, end-lasting mechanism comprising wipers for wiping the margin of an upper inwardly over the bottom of a last at opposite sides of an end of the last, members supporting said wipers and mounted for swinging movements each about an axis extending heightwise of the last to operate the wipers, and rolls carried by said members for laying over the bottom of the last portions of the margin of the upper near the ends of the wipers, said rolls being arranged to engage and act on the margin of the upper before said wipers begin to wipe the upper inwardly.

52. In a lasting machine, end-lasting mechanism comprising wipers for wiping the margin of an upper inwardly over the bottom of a last at opposite sides of an end of the last, members supporting said wipers and mounted for swinging movements each about an axis extending heightwise of the last to operate the wipers, and devices carried by said members for laying over the bottom of the last portions of the margin of the upper near the ends of said wipers, said devices comprising rolls yieldingly movable heightwise of the last relatively to the wipers and springs for pressing said rolls upon the shoe bottom.

53. In a lasting machine, end-lasting mechanism comprising wipers for wiping the margin of an upper inwardly over the bottom of a last at opposite sides of an end of the last, members supporting said wipers and mounted for swinging movements each about an axis extending heightwise of the last to operate the wipers, and devices carried by said members for laying over the bot-

tom of the last portions of the margin of the upper near the ends of said wipers, said devices each comprising a pair of rolls for engaging the margin of the upper and a holder for the rolls having a portion thereof located between the rolls and flush with their peripheries.

54. In a lasting machine, end-lasting mechanism comprising wipers for wiping the margin of an upper inwardly over the bottom of a last at opposite sides of an end of the last, members supporting said wipers and mounted for swinging movements each about an axis extending heightwise of the last to operate the wipers, and devices carried by said members for laying over the bottom of the last portions of the margin of the upper near the ends of said wipers, said devices comprising rolls for engaging the margin of the upper, arms supporting said rolls and mounted to swing heightwise of the last, and springs for holding said arms initially in positions determined by contact with the wipers and yieldable in response to pressure of the shoe on the rolls.

55. In a lasting machine, the combination with a band for clamping an upper around an end of a last, of wipers movable to wipe the margin of the upper inwardly over the bottom of the last at opposite sides of the end of the last, rolls also movable inwardly to lay portions of the margin of the upper over the bottom of the last, said rolls being arranged to be deflected heightwise of the last by contact with said band, and springs against the resistance of which the rolls are thus deflected.

56. In a lasting machine, the combination with a band for clamping an upper around an end of a last, of wipers for wiping the margin of the upper inwardly over the bottom of the last at opposite sides of the end of the last, members supporting said wipers and movable each about an axis extending heightwise of the last to operate them, and rolls carried by said members for laying over the bottom of the last portions of the margin of the upper near the ends of said wipers, said rolls being arranged to be deflected heightwise of the last by contact with said band.

57. In a lasting machine, end-lasting mechanism comprising wipers movable lengthwise and laterally of a last to wipe the margin of an upper around an end of the last inwardly over the bottom of the last, other wipers movable to wipe the margin of the upper inwardly at the sides of the end of the last and relatively to which said first-named wipers are movable lengthwise of the last, said other wipers being mounted for operative swinging movements each about an axis extending heightwise of the last, and rolls movable inwardly with said other wipers to lay portions of the margin of the upper over the bottom of the last.

58. In a lasting machine, end-lasting mechanism comprising wipers movable lengthwise and laterally of a last to wipe the margin of an upper around an end of the last inwardly over the bottom of the last, other wipers movable to wipe the margin of the upper inwardly at the sides of the end of the last and relatively to which said first-named wipers are movable lengthwise of the last, arms supporting said other wipers and movable each about an axis extending heightwise of the last to operate said wipers, and rolls carried by said arms for laying inwardly over the bottom of the last portions of the margin of the upper near the ends of said other wipers.

59. In a lasting machine, end-lasting mechanism comprising wipers movable lengthwise and

- laterally of a last to wipe the margin of an upper around an end of the last inwardly over the bottom of the last, other wipers movable to wipe the margin of the upper inwardly at the sides 5 of the end of the last and relatively to which said first-named wipers are movable lengthwise of the last, said other wipers being mounted for operative swinging movements each about an axis extending heightwise of the last, and rolls 10 movable inwardly with said other wipers in locations near the ends of the latter to lay portions of the margin of the upper over the bottom of the last, said rolls being arranged to engage and act on the upper before said other wipers begin to 15 wipe the upper inwardly.
60. In a lasting machine, the combination with means for lasting the forepart of a shoe on a last, of members arranged to serve as abutments in engagement with the upper at the sides of the 20 last to position the forepart of the last and shoe laterally for the lasting operation, and mechanism for withdrawing said members from their operative positions after the positioning of each last and shoe.
61. In a lasting machine, the combination with means for lasting the forepart of a shoe on a last, of members arranged to serve as abutments in engagement with the upper at the sides of the 25 last to position the forepart of the last and shoe laterally for the lasting operation, and mechanism for moving said members widthwise of the last to withdraw them from their operative positions after the positioning of each last and shoe.
62. In a lasting machine, the combination with means for lasting the forepart of a shoe on a last, of gaging means for positioning the forepart of the last for the lasting operation, means movable from an idle position to a position over the bottom of the shoe for controlling the shoe in the 30 lasting operation, and mechanism for withdrawing said gaging means from its operative position in response to such movement of said controlling means.
63. In a lasting machine, the combination with means for lasting the forepart of a shoe on a last, of members arranged to serve as abutments to position the forepart of the last laterally for the lasting operation, an arm mounted for swinging 35 movement from an idle position to a position over the bottom of the shoe and having thereon means for controlling the shoe in the lasting operation, and mechanism arranged to be operated by the swinging of said arm to withdraw said members from their operative positions.
64. In a lasting machine, the combination with means for lasting the forepart of a shoe on a last comprising wipers for wiping the margin of the toe end of the upper inwardly over the bottom 40 of the last, and means for clamping the margin of the upper on said wipers, of gaging means over said wipers arranged to position the forepart of the last for the lasting operation, and mechanism for withdrawing said gaging means from 45 an operative position to make way for said upper clamping means.
65. In a lasting machine, the combination with means for lasting the forepart of a shoe on a last comprising wipers for wiping the margin of the toe end of the upper inwardly over the bottom 50 of the last, of an arm mounted for movement from an idle position to a position over the bottom of the last and having thereon means for clamping the margin of the upper on said wipers, 55 means over said wipers for gaging the position 75 of the toe end of the last for the lasting operation, and mechanism operative in response to the movement of said arm for withdrawing said gaging means from its operative position.
66. In a lasting machine, the combination with 5 means for lasting the forepart of a shoe on a last, of devices arranged to position the forepart of the last laterally for the lasting operation, said devices being connected together for equalized swinging movements toward and from each 10 other, a bracket mounted for swinging movement separately from said devices and adjustably connected to one of the devices, and mechanism for swinging said bracket to withdraw said devices from their operative positions after the position- 15 ing of each last.
67. In a lasting machine, the combination with means for lasting the forepart of a shoe on a last, of devices arranged to position the forepart of the last laterally for the lasting operation, said 20 devices being connected together for equalized swinging movements toward and from each other, a bracket mounted for swinging movement separately from said devices and adjustably connected to one of the devices, a member connected 25 to said bracket for swinging it to withdraw said devices from their operative positions, a latch on said member for holding the bracket in an initial position, and mechanism connected to said latch for first withdrawing the latch from holding position and for then operating said member to 30 swing the bracket.
68. In a lasting machine, the combination with means for laying the margin of the toe end of an upper inwardly over an insole on a last, of a 35 device for clamping the margin of the insole around its toe end on the bottom of the last, said device comprising a plurality of members movable relatively to one another in outward directions toward the edge of the toe end of the 40 insole while in contact with the insole, and means for thus relatively moving said members to cause the margin of the insole to lie smooth upon the bottom of the last.
69. In a lasting machine, the combination with 45 means for laying the margin of the toe end of an upper inwardly over an insole on a last, of a device for clamping the margin of the insole around its toe end on the bottom of the last, said device comprising members mounted for swinging move- 50 ments widthwise of the last each about an axis extending heightwise of the last, and means for moving said device as a whole lengthwise of the last toward the edge of the insole and for also swinging said members apart while in contact 55 with the insole to cause the margin of the insole to lie smooth upon the bottom of the last.
70. In a lasting machine, the combination with means for laying the margin of the toe end of an upper inwardly over an insole on a last, of a de- 60 vice for clamping the margin of the toe end of the insole on the bottom of the last, said device comprising members mounted for swinging move- 65 ments widthwise of the last each about an axis extending heightwise of the last, levers extending lengthwise of the last and connected to said members for controlling them, means for moving said levers bodily lengthwise of the last to move said clamping device toward the edge of the insole while in contact with the insole, and cam 70 means arranged to act on said levers in their bodily movements to swing said members out- 75 wardly toward the side edges of the insole.
71. In a lasting machine, the combination with lasting means for conforming the toe end of an 75

upper to the contour of a last and for laying its margin inwardly over an insole on the last, and a member movable to depress the last and shoe relatively to said lasting means, of a device carried by said member for clamping the margin of the insole around its toe end on the bottom of the last, and automatic means for moving said device outwardly toward the edge of the insole while in contact with the margin of the insole after the depression of the last.

72. In a lasting machine, the combination with lasting means for conforming the toe end of an upper to the contour of a last and for laying its margin inwardly over an insole on the last, and a member movable to depress the last and shoe relatively to said lasting means, of a device carried by said member for clamping the margin of the toe end of the insole on the bottom of the last, said device comprising members movable relatively to each other widthwise of the last, and means for moving said device as a whole lengthwise of the last toward the edge of the toe end of the insole and for also moving said members outwardly toward the side edges of the insole while in contact with the insole after the depression of the last.

73. In a lasting machine, the combination with lasting means for conforming the toe end of an upper to the contour of a last and for laying its margin inwardly over an insole on the last, and a member movable to depress the last and shoe relatively to said lasting means, of a device carried by said member for clamping the margin of the toe end of the insole on the bottom of the last, mechanism also carried by said member for imparting to said device movement outwardly toward the edge of the insole while in contact with the insole, and means into operative relation to which said mechanism is carried by the movement of said member for thereafter operating said mechanism.

74. In a lasting machine, the combination with wipers for wiping the margin of the toe end of an upper inwardly over an insole on a last, and mechanism for operating said wipers, of a device for clamping the margin of the toe end of the insole on the bottom of the last, and means arranged to be operated by said wiper-operating mechanism to impart to said device movement outwardly toward the edge of the insole while in contact with the insole.

75. In a lasting machine, the combination with wipers for wiping the margin of the toe end of an upper inwardly over an insole on a last, mechanism for operating said wipers, and a member movable to depress the last and shoe relatively to the wipers, of a device carried by said member for clamping the margin of the toe end of the insole on the bottom of the last, and means also carried by said member and arranged to be operated by said wiper-operating mechanism to impart to said device movement outwardly toward the edge of the insole while in contact with the insole after the depression of the last.

76. In a lasting machine, the combination with wipers for wiping the margin of the toe end of an upper inwardly over an insole on a last, of a device for clamping the margin of the insole around its toe end on the bottom of the last, said device comprising a plurality of members movable relatively to one another in outward directions toward the edge of the insole while in contact with the insole, and means for thus relatively moving said members to cause the margin of the insole to lie smooth upon the bottom of the last, said mem-

bers being arranged also to press the margin of the upper upon the wipers in the overwiping operation.

77. In a lasting machine, the combination with wipers for wiping the margin of the toe end of an upper inwardly over an insole on a last, of a device for clamping the margin of the toe end of the insole on the bottom of the last, said device comprising members mounted for swinging movements widthwise of the last each about an axis 10 extending heightwise of the last, and means for moving said device lengthwise of the last toward the edge of the insole and for also swinging said members apart while in contact with the insole to cause the margin of the insole to lie smooth upon the bottom of the last, said device being arranged also to press the margin of the upper upon the wipers in the overwiping operation and to be forced away from the insole by wedging action of the wipers thereon.

78. In a lasting machine, the combination with wipers for wiping the margin of the toe end of an upper inwardly over an insole on a last, of a device arranged to clamp the margin of the toe end of the insole on the bottom of the last and 25 also to act as a spreader in contact with the margin of the upper in the overwiping operation, and means for moving said device outwardly along the bottom face of the insole as the wipers receive their operative movement.

79. In a lasting machine, the combination with wipers for wiping the margin of the toe end of an upper inwardly over an insole on a last, of a device arranged to clamp the margin of the toe end of the insole on the bottom of the last and 35 also to act as a spreader in contact with the margin of the upper in the overwiping operation, said device comprising a plurality of relatively movable insole-engaging members, and means for moving said members relatively to one another in 40 outward directions along the bottom face of the insole as the wipers receive their operative movement.

80. In a lasting machine, the combination with wipers for wiping the margin of the toe end of an 45 upper inwardly over an insole on a last, of a device arranged to clamp the margin of the toe end of the insole on the bottom of the last and also to act as a spreader in contact with the margin of the upper in the overwiping operation, 50 said device comprising insole-engaging members mounted for swinging movements widthwise of the last each about an axis extending heightwise of the last, and means for moving said device lengthwise of the last toward the edges of 55 the wipers and for also swinging said members apart toward said edges.

81. In a lasting machine, the combination with wipers for wiping the margin of the toe end of an upper inwardly over an insole on a last, of a 60 device arranged to clamp the margin of the toe end of the insole on the bottom of the last and also to act as a spreader in contact with the margin of the upper in the overwiping operation, said device comprising insole-engaging members 65 mounted for swinging movements widthwise of the last each about an axis extending heightwise of the last, crossed levers connected to said members for controlling them, and means for moving said levers bodily to carry said device 70 lengthwise of the last toward the edges of the wipers at the end of the toe and for also swinging them to move said members outwardly toward the edges of the wipers at the sides of the toe.

82. In a lasting machine, the combination with 75

wipers for wiping the margin of the toe end of an upper inwardly over an insole on a last, and a member movable to depress the last and shoe relatively to said wipers, of a device carried by 5 said member and arranged to clamp the margin of the toe end of the insole on the bottom of the last and also to act as a spreader in contact with the margin of the upper in the overwiping operation, and means for moving said device outwardly along the bottom face of the insole after 10 the depression of the last.

83. In a lasting machine, the combination with wipers for wiping the margin of the toe end of an upper inwardly over an insole on a last, and a 15 member movable to depress the last and shoe relatively to said wipers, of a device carried by said member and arranged to clamp the margin of the toe end of the insole on the bottom of the last and also to act as a spreader in contact with 20 the margin of the upper in the overwiping operation, said device comprising a plurality of relatively movable insole-engaging members, and means for moving said members relatively to one another in outward directions along the bottom 25 face of the insole after the depression of the last.

84. In a lasting machine, the combination with wipers for wiping the margin of the toe end of an upper inwardly over an insole on a last, and 30 a member movable to depress the last and shoe relatively to said wipers, of a device carried by said member and arranged to clamp the margin of the toe end of the insole on the bottom of the last and also to act as a spreader in contact with 35 the margin of the upper in the overwiping operation, said device comprising a plurality of relatively movable insole-engaging members, mechanism also carried by said shoe-depressing member for moving said insole-engaging members relatively to one another in outward directions along 40 the bottom face of the insole, and means into operative relation to which said mechanism is carried by the movement of said shoe-depressing member for thereafter imparting to said mechanism its operative movement.

85. In a lasting machine, the combination with wipers for wiping the margin of the toe end of an upper inwardly over an insole on a last, and 45 means for effecting relative movement of said wipers and the last heightwise of the last, of means for clamping the margin of the toe end of the upper upon said wipers to apply a pull to the upper by said relative movement, and a device arranged to clamp the margin of the toe end 50 of the insole on the bottom of the last and also to act as a spreader in contact with the margin of the upper in the overwiping operation.

86. In a lasting machine, the combination with wipers for wiping the margin of the toe end of an upper inwardly over an insole on a last, and 60 means for effecting relative movement of said wipers and the last heightwise of the last, of means for clamping the margin of the toe end of the upper upon said wipers to apply a pull to the upper by said relative movement, a device 65 arranged to clamp the margin of the toe end of the insole on the bottom of the last and also to act as a spreader in contact with the margin of the upper in the overwiping operation, and means 70 for moving said device outwardly along the bottom face of the insole in automatically determined time relation to the overwiping movement of the wipers.

87. In a lasting machine, the combination with 75 wipers for wiping the margin of the toe end of

an upper inwardly over an insole on a last, and means for effecting relative movement of said wipers and the last heightwise of the last, of means for clamping the margin of the toe end of the upper upon said wipers to apply a pull to the upper by said relative movement, and a device 5 arranged to act thereafter as a spreader on the portion of the margin of the upper previously engaged by said clamping means to press the upper yieldingly over the edges of the wipers in 10 the overwiping operation of the wipers.

88. In a lasting machine, the combination with wipers for wiping the margin of the toe end of an upper inwardly over an insole on a last, and 15 means for effecting relative movement of said wipers and the last heightwise of the last, of means for clamping the margin of the toe end of the upper upon said wipers to apply a pull to the upper by said relative movement, a device arranged to act thereafter as a spreader on the portion 20 of the margin of the upper previously engaged by said clamping means to press the upper over the edges of the wipers in the overwiping operation, and means for moving said device outwardly along the bottom face of the insole in 25 automatically determined time relation to the overwiping operation.

89. In a lasting machine, the combination with wipers for wiping the margin of the toe end of an upper inwardly over an insole on a last, and 30 means for effecting relative movement of said wipers and the last heightwise of the last, of means for clamping the margin of the toe end of the upper upon said wipers to apply a pull to the upper by said relative movement, a device 35 arranged to clamp the margin of the toe end of the insole on the bottom of the last and also to act as a spreader in contact with the margin of the upper in the overwiping operation, and means for moving said device in an outward direction 40 lengthwise of the shoe in automatically determined time relation to the overwiping movement of the wipers and for also imparting to said upper-clamping means a movement in the same direction.

90. In a lasting machine, the combination with wipers for wiping the margin of the toe end of an upper inwardly over an insole on a last, and 45 a member movable to depress the last relatively to said wipers, of a device carried by said member for clamping the margin of the upper upon the wipers to apply a pull to the upper as the last is depressed, and another device carried by said member for clamping the margin of the toe end of the insole on the bottom of the last and for 55 also pressing the upper on the wipers to serve as a spreader in contact therewith in the overwiping operation.

91. In a lasting machine, the combination with wipers for wiping the margin of the toe end of an upper inwardly over an insole on a last, and 60 a member movable to depress the last relatively to said wipers, of a device carried by said member for clamping the margin of the upper upon the wipers to apply a pull to the upper as the last is 65 depressed, another device carried by said member for clamping the margin of the toe end of the insole on the bottom of the last and for also pressing the margin of the upper on the wipers to serve as a spreader in contact therewith in 70 the overwiping operation, and mechanism for moving said other device outwardly toward the edge of the insole while in contact with the insole.

92. In a lasting machine, the combination with 75

wipers for wiping the margin of the toe end of an upper inwardly over an insole on a last, and a member movable to depress the last relatively to said wipers, of a device carried by said member 5 for clamping the margin of the upper upon the wipers to apply a pull to the upper as the last is depressed, another device carried by said member for clamping the margin of the toe end of the insole on the bottom of the last and for also 10 pressing the margin of the upper on the wipers to serve as a spreader in contact therewith in the overwiping operation, said other device comprising a plurality of relatively movable insole-engaging members, and means for moving said members relatively to one another along the bottom 15 face of the insole toward the edge of the insole in automatically determined time relation to the operative movement of the wipers.

93. In a lasting machine, the combination with wipers for wiping the margin of the toe end of an upper inwardly over an insole on a last, and a member movable to depress the last relatively to said wipers, of a device carried by said member 5 for clamping the margin of the upper upon the wipers to apply a pull to the upper as the last is depressed, another device carried by said member for clamping the margin of the toe end of the insole on the bottom of the last and for also 10 pressing the margin of the upper over the edges of the wipers to serve as a spreader in contact therewith in the overwiping operation, and mechanism arranged to move both said devices in the same direction lengthwise of the last in 15 automatically determined time relation to the operative movement of the wipers.

BERNHARDT JORGENSEN.
